CAR COUPLING

John Gumkowski, Johnston City, Ill., assignor of
one-half to Michael Shannon, Johnston City,
Ill.

Application May 17, 1937, Serial No. 143,093

2 Claims. (Cl. 213—205)

This invention relates to improvements in car couplings.

The main object of the invention is to provide a coupling for railroad cars and the like in which coupling the action is simple and positive and takes place or is performed automatically as the cars move together.

Another object is to provide a coupling of this kind in which the connection formed is flexible to a high degree in both horizontal and vertical planes so as to freely permit and allow for the swaying and play of the cars caused by inequalities and curves in the track upon which they run.

Another object is to provide a coupling which may be readily and safely operated to uncouple the cars without necessitating that the operator or workman place his hands or body in such position as to be jeopardized, the arrangement being such that this action is accomplished by a handle or lever located at a point remote from the actual coupling elements.

A further object is to provide a coupling including a link resiliently and pivotally connected to and extended from the car, a housing to receive the said link, a pin pivotally mounted in the housing and depended into the path of the link and adapted to engage the same to form a connection between the housing and link, and a shaft located at a point remote from the pin and operatively connected to the pin for raising the same out of engagement with the link.

A further object is to provide a coupling of the foregoing characteristics in a simple, strong and durable form.

With these and other objects in view the invention resides in the novel construction and arrangement of parts as hereinafter fully set forth and claimed, reference being had to the accompanying drawings wherein:

Figure 1 is a side elevation of the coupling.

Figure 2 is an enlarged section along the line 2—2 in Figure 1.

Figure 3 is an enlarged vertical and longitudinal section through the coupling showing the position of the parts as the cars move together and just prior to the coupling of the cars.

Figure 4 is a view similar to Figure 3 showing the parts in the coupled or connected position.

Figure 5 is a section along the line 5—5 in Figure 3.

Referring now with more particularity to the drawings the reference character 1 designates an elongated rectangular coupling box or housing which is secured in any suitable manner to one

end of the railroad car indicated generally at A. This housing 1 includes the sides 2, bottom 3, top 4 and end 5, the other end outwardly disposed end 6 being open for the entrance of the coupling link to be described. An operating shaft 7 is journaled horizontally through the sides 2 of the housing 1 at a point remote from the open end 6 and projects at its ends from the housing as shown. An arm 8 is secured centrally on the operating shaft 7 and is radially extending therefrom forwardly or outwardly toward the open end of the housing. A supporting rod 9 is secured horizontally in the free end of the arm 8 which is forked as shown at 10 and the rod plays at its ends in arcuate grooves 11 cut in the inner faces of the housing sides 2 with their radii centered on the center of the operating shaft 7, the arrangement being such that the said rod 9 may be raised by slightly rotating the operating shaft 7 as will be understood. A locking or coupling pin 12 is pivotally connected by one end to the supporting rod 9 and depends therefrom, the upper end of the pin preferably being disposed between the forks on the end of the arm 8. The grooves 11 terminate at their lower ends at such point that the lower end of the pin 12 normally depends into a slot 13 cut in the bottom 3 of the coupling housing 1, the said slot being so disposed and of such length that the pin rests in engagement with the forward or outer end thereof which serves as a stop, but may be swung rearwardly or inwardly and upwardly and will clear the rear or inner end of the slot without raising the rod 9 as shown in Figure 3.

A base plate or attaching element 14 is mounted on or extended from the end of the car B and a bracket 15 is secured by its foot portion 16 to this base plate, the bracket having an arm 17 disposed above and parallel to the base plate as shown. A bolt or similar fastener 18 is passed vertically through the arm 17 and base plate 14 and has a nut 19 at its lower end. An elongated open coupling link 21 having end bights 22 and 23 is provided, and a loop 24 formed of flat strip material encircles the link adjacent the bight 22. The loop 24 has medially located and aligned apertures 25 through which the bolt 18 loosely passes. An expansion coil spring 26 is coiled around the bolt 18 and is braced between the arm 17 of the bracket 15 and the loop 24. The arrangement is such that the link 21 is loosely pivoted on the bolt 18 and may swing in a lateral plane thereon and may also move upward or downward at its outer end to some degree. The spring 26 allows these movements of the

link 21 and will normally retain the link in the horizontal position shown.

In operation and as the ends of the cars A and B move together the outer end of the link 21 will enter the open end 6 of the housing 1 and will strike the locking pin 12 forcing the same inward and upward at its lower end clear of the slot 13 as shown in Figure 3 until the link passes beneath the pin. The pin 12 will fall forward 5 within the bight 23 of the link 21 and will thus prevent the link from pulling out forwardly from the housing as the lower end of the pin comes in engagement with the forward end of the slot 13 or the forward portion 3a of the bottom 3 10 forming the forward margin of the slot. This marginal portion 3a thus serves as a stop limiting the forward swing of the pin 12. The cars are thus held connected together but at the same time the connection is sufficiently flexible to 15 permit the swaying and turning of the cars in motion, this by virtue particularly of the connection of the link to the bolt 18 as described. The ends of the supporting rod 9 slidably engage the sides of the box or housing, thus bracing the 20 elements against severe lateral strain that might otherwise throw them out of working alignment. To release the link 21 forwardly the operating shaft 7 is rotated slightly swinging the arm 8 upward and raising the locking pin 12 out of the 25 bight of the link. To facilitate this rotation of the operating shaft 7 cranks or handles 27 are provided in the ends thereof. It will be noted that the operation of uncoupling the cars is thus accomplished without placing the hands near the 30 actual coupling elements, thereby effectually preventing injury to the operator. As an aid to guiding the link 21 into the open end 6 of the housing 1 flaring or diverging guide wings 28 are secured to and extended from the sides 2 as 35 shown. It is understood that each car has one coupling housing 1 and one link 21 and its connection as described disposed at opposite ends of the car to engage the coupling elements of adjacent cars in conventional manner.

While I have herein set forth a certain preferred embodiment of my invention it is understood that I may vary from the same in minor 40

structural details so as best to construct a practical device for the purposes intended, not departing from the spirit of the invention and within the scope of the appended claims.

I claim:

1. In a car coupling assembly of the kind described, a base plate for mounting upon an end of a car, an angular bracket having a foot portion secured to the base plate and having an arm extended outwardly therefrom and in parallelism with the base plate, an elongated open coupling link having one end positioned between the base plate and the said arm, a flat spring-supporting loop embracing this end of the coupling link, a bolt passed through the bracket arm, 10 through the flat spring-supporting loop of the underlying end of the coupling link and through the base plate, and an expansion coil spring seated over the bolt and braced at its ends between the bracket arm and the upper side of the spring-supporting loop, whereby the coupling link is maintained in a substantially horizontal alignment for engaging at its free open end a co-operating coupling assembly at the end of an adjacent car.

2. In a car coupling assembly including a horizontally disposed base plate at one end of a car and a bracket upon the base plate having an outwardly extended arm spaced from the base plate, there being a bolt passed down through the outer 20 end of the arm and through the base plate, and there being an elongated open coupling link having one end embracing the said bolt, a flat spring supporting loop embracing the bolt engaging end of the coupling link with the lower 25 side of the loop in contact with the upper face of the base plate, and an expansion coil spring seated over the bolt and braced at its ends between the bracket arm and the upper face of the spring supporting loop around the end of the 30 coupling link, whereby the coupling link is horizontally and yieldably supported in substantially horizontal alignment for engaging at its free end a cooperating coupling assembly at the end of another car.

JOHN GUMKOWSKI.
